UNITED STATES PATENT OFFICE.

JOHN B. VAN HOUTEN, OF NEWARK, NEW JERSEY.

DESIGN FOR AN EAR-RING PENDANT.

SPECIFICATION forming part of Design No. 14,924, dated March 25, 1884.

Application filed February 8, 1884. Term of patent 7 years.

To all whom it may concern:

Be it known that I, JOHN B. VAN HOUTEN, a citizen of the United States, residing at Newark, in the county Essex and State of New Jersey, have invented and produced a new and original Design for Ear-Ring Pendants; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

In said drawings, Figure 1 is a front, and 15 Fig. 2 a side, elevation of an ear-ring pendant. These are deemed sufficient to fully illustrate the said design, which consists in the ear-ring pendant having the configuration hereinafter set forth.

In said drawings is shown a globular pendant of an ear-ring, having at each side thereof indentations b b , or breaks in its regular outline. The edges b' b' , when viewed in front elevation, flare outwardly and downwardly from a point near where the pendant is secured 20 to the ear-plate e . From the indented portions b ridges c extend upwardly and meet at 25 said ear-plate e .

What I claim is—

The design for an ear-ring pendant, herein 30 set forth and shown.

In testimony that I claim the foregoing I have hereunto set my hand this 6th day of February, 1884.

JOHN B. VAN HOUTEN.
